UNITED STATES PATENT OFFICE.

JULIA E. TWOHEY, OF BOSTON, MASSACHUSETTS.

PIE PLATE.

Application filed August 4, 1926. Serial No. 126,987.

This invention relates to a pie plate provided with a gutter for catching the juices of berries and like juicy materials which may overflow the pie plate proper during 5 the baking process.

The invention has for its object to provide a pie plate of this character which can be made and sold at a minimum price, and which is provided with a gutter integral 10 with the pie plate proper and which has its outer edge located at a lower level than the rim of the pie plate proper and which gutter is also of relatively great capacity as will be described.

15 To this end the gutter and pie plate are stamped or pressed from a single piece of sheet metal, preferably aluminum, and the pie plate proper is provided with an outwardly extended substantially flat rim below and within the outer circumference of 20 which is located the upper portion of the inner wall of the gutter, which is connected with the outer circumference of the rim of the pie plate proper by a relatively short 25 flange which is extended downward and inwardly toward the outer wall of the pie plate proper.

The particular features of the invention will be pointed out in the claim at the end of 30 this specification.

Fig. 1 is a plan view of a pie plate embodying this invention, and

Fig. 2, a view in side elevation and section of the pie plate shown in Fig. 1.

35 Referring to the drawing *a* represents the pie plate proper and *b* the gutter. The pie plate proper *a* is provided with a bottom 10 and with an upwardly and outwardly extended annular wall 12, which is provided 40 at its upper end with an outwardly extended substantially flat rim 13.

The gutter *b* is provided with an outer wall 14 and with an inner wall 15, and the upper ends of said walls are located at a 45 lower level than the rim 13, as clearly shown in Fig. 2.

The inner wall 15 is inclined upwardly toward the inclined wall 12 of the pie plate proper and forms therewith a substantially 50 A-shaped annular channel or space, and the upper end of the inclined wall 15 is located below the rim 13 and within the outer circumference thereof and is connected with said outer circumference by a relatively 55 short flange 17, which extends downward

and inwardly from the outer circumference of the rim 13.

The outer wall 14 of the gutter is folded to form a bead 18 which reenforces the outer edge of the gutter and provides a neat finish for the same.

The outer wall 14 of the gutter *b* may and preferably will be provided with a depression 20 which forms a pouring spout or nose for the gutter.

The gutter *b* is relatively shallow with relation to the depth of the pie plate proper *a*, so as not to offer an obstruction to the heat directly contacting with the annular wall 12 of the pie plate proper to substantially its upper end, so that the crust lying upon the rim 13 can be baked in a crisp and efficient manner and is not soggy by reason of lack of baking.

By making the inner wall 15 inclined and 75 extending it toward the pie plate proper so that its upper end is within the outer circumference of the rim 13, the capacity of the gutter is increased without increasing the depth of the gutter or the diameter of its 80 outer wall.

This result is obtained in a one-piece sheet metal construction by means of the inclined flange 17 connecting the outer circumference of the rim 13 with the upper end of the 85 inclined inner wall 15 of the gutter, and said flange at the same time serves to stiffen the rim 13 of the pie plate proper.

The upper edge of the outer wall of the gutter being below the level of the rim 13 90 enables the dough which is to form the crust of the pie to be trimmed off with a knife in the manner now commonly practiced with the ordinary pie plate, which knife may rest upon the outer wall of the gutter while in 95 use.

By reference to Fig. 2, it will be seen that the outer surface of the inclined wall 12 and the under surface of the rim 13 of the pie plate proper are exposed to the heat in the 100 oven in the same manner as the ordinary pie plate and that the gutter does not interfere with the baking operation, nor with the trimming operation.

The construction of pie plate and gutter 105 herein shown enables them to be stamped or pressed from a single piece of sheet metal and thereby produced at such relatively low cost as to enable them to be commercially exploited inasmuch as the downward and 110

inwardly extended flange 17 forms a yielding or resilient connection between the inner wall 15 of the gutter and the outer edge of the rim 13, which prevents fracture of the metal sheet when subjected to the pressure of the press.

What I claim is:

A one-piece pie plate and gutter therefor, comprising a pie plate proper provided with a bottom and an inclined annular wall extended upwardly and outwardly from said bottom and provided at its upper end with an outwardly extended rim, and a gutter

having an outer wall located below the level of said rim and an inner wall having its upper end within the outer circumference of said rim and below the latter, and an annular flange extended downward and inwardly from the outer circumference of the said rim and connecting the latter with the upper end of the inner wall of said gutter.

In testimony whereof, I have signed my name to this specification.

JULIA E. TWOHEY.
